UNITED STATES PATENT OFFICE.

BENJAMIN KUGLER, OF CHICAGO, ILLINOIS.

TERMINAL COUPLING AND ANCHORAGE FOR WINDOW-CLEANERS' HARNESS.

Application filed May 24, 1922. Serial No. 563,459.

To all whom it may concern:

Be it known that I, BENJAMIN KUGLER, a citizen of the United States, residing at Chicago, in the county of Cook, State of Illinois, have invented new and useful Improvements in Terminal Couplings and Anchorage for Window-Cleaners' Harness, of which the following is a specification.

My invention has reference, in its broad aspect, to improvements in couplings and anchoring devices complementary thereto for attaching the harness used by window cleaners' and others to a suitable base; and more particularly the present embodiment of my invention is designed to provide a unitary double anchorage for use in conjunction with the so-called double window, and an improved coupling which is readily detachable, but which is normally positively locked in position upon the anchorage.

In order to impart a clear understanding of the principal objects of my present invention it is pointed out that devices heretofore known in the art have not attained a unitary anchorage for window cleaners' harness which is particularly adapted for use with a double window, consequently it has been necessary to mount upon the dividing or common frame of the windows, or upon the column of separating masonry, a pair or more of independent anchorages. This not only increases expense and adds to the unsightly appearance of the windows, but it doubles or triples the element of danger from worn fittings. Furthermore, my coupling in addition to being peculiarly adapted for use with my anchorage, is devised to eliminate the prying and twisting strain which so often results in weakening the harness and the fittings.

From the foregoing it will be seen that the principal objects of my invention are: first, to provide a double, unitary anchorage for window cleaners' harness; second, to attain by my anchorage the maximum safety and simplicity while reducing the initial cost; third, to afford a double anchorage with a single attaching element; fourth, to provide a detachable terminal coupling for window cleaners' harness which will be positively locked upon the anchorage; and, fifth, to provide a coupling which will reduce or eliminate the prying and twisting strain upon the anchorage and harness.

The structural elements employed to ac-

complish the above and other results and objects will be hereinafter more fully described in detail and specifically pointed out in the claims appended hereunto, and forming a part of this specification.

In the accompanying drawings wherein is illustrated the preferred embodiment of my invention:

Figure 1, is a perspective view of my anchorage and coupling assembly.

Figure 2, is a top view of the assembly, partly in section, showing the locking engagement.

Figure 3, is a vertical section of the assembly, and,

Figure 4, is a side or edge view of the anchorage head.

Like characters of reference refer to like or similar parts throughout the several views of the drawings, in which:

The numeral (1) designates the body of the anchorage head, which is provided with a rectangular central opening (2) through which the securing bolt (3) is trained. The end of the shank of the bolt adjacent its head is squared to fit within the rectangular opening (2) and when the anchorage is mounted the bolt is disposed through the dividing, or common frame of the windows (not shown) or through the column of separating masonry. Formed integrally with, and flared upwardly and outwardly from the body (1) upon either side edge thereof are opposed pairs of studs (4). The studs (4) are formed with heads (5) and enlargements (6) adjacent their bases. It will be seen that when the anchorage is mounted a pair of the studs (4) will be directed toward each of the adjacent windows. The ends of the body are elongated and rounded as at (7) and provided with openings for the reception of retaining screws.

The coupling used with my anchorage comprises an elongated body (8), formed with a centrally located longitudinal slot (9) opening at one end. The material of the upper portion of the body around the periphery of the slot is cut away to form a recess (10), the walls of which provide a track for the heads (5) of the studs (4) when the coupling is mounted upon the anchorage. Formed integrally with the body intermediate its extremities and rising at right angles therefrom is an eye (11) for receiving one terminal end (not shown) of a window cleaners' harness, and the base of

the eye is cut away as at (12) to permit passage of the heads (5) of the studs thereunder. The locking device used with my coupling comprises a pawl (13) mounted 5 upon a pin (14) journalled through the sides (15) of a support therefor which is formed integrally with the body (8). The legs (16) of the support extend upwardly and rearwardly from the body and are cut 10 away as at (17) to permit the heads of the studs to pass thereunder. An eye (18) is also formed on the support to be engaged by a portion of the harness (not shown), and a coil spring (19) bearing against the pawl 15 (13) causes the same to normally obstruct the track formed by the recess (10) and close the slot (9).

In operation, the anchorage having been mounted in its proper position, the coupling 20 is disposed with the track formed by the recess (10) in alignment with certain of the heads (5) of the studs (4). It is thereupon moved downwardly until the heads (5) have passed within the slot (9) and the pawl 25 (13) has seated itself to obstruct the return thereof. In this position accidental dislodgement of the coupling is positively prevented, as the pawl must first be raised, and furthermore, prying and twisting strain is 30 greatly reduced. It is pointed out that strain upon the anchorage is equalized when two window washers are harnessed thereto. While in the foregoing, there has been 35 illustrated and described such combination and arrangement of elements as constitute the preferred embodiment of my invention, it is nevertheless desired to emphasize the fact that interpretation of the invention should only be conclusive when made in the 40 light of the subjoined claims.

Having described my invention and its objects with such attention to detail as will thoroughly acquaint one skilled in the art with its construction and advantages, I 45 claim:

1. A device of the character described comprising an anchorage formed with a body, opposed pairs of studs arranged respectively upon opposite side edges of the 50 body, and means extending through the body between the respective pairs of studs for attaching the body to a suitable base.

2. A device of the character described comprising an anchorage formed with a body 55 having a centrally located opening, opposed pairs of studs arranged respectively upon

opposite side edges of the body, each pair of said studs being flared outwardly from the body and away from the central opening therein, and means extending through the 60 central opening in the body between the respective pairs of studs for attaching the body to a suitable base.

3. A device of the character described comprising an anchorage formed with a body 65 having a centrally located opening, opposed pairs of studs arranged respectively upon opposite side edges of the body, and said studs provided each with two enlargements constituting a head and an abutment 70 respectively, the abutment being a distinct and abrupt enlargement of the material of the studs and body, and means extending through the central opening in the body between the respective pairs of studs for 75 attaching the body to a suitable base.

4. A device of the character described comprising an elongated body provided with a longitudinal slot, the material of the 80 upper portion of the body adjacent the slot being cut away to form a recess for receiving an anchorage for the body, and a spring pressed pawl for locking the anchorage within the slot and recess.

5. In combination with an anchorage 85 including a body formed with opposed pairs of studs on opposite side edges thereof, of a coupling formed with recesses for receiving the studs and means carried by the coupling for locking the studs within the recesses. 90

6. In combination with an anchorage including a body formed with opposed pairs of studs on opposite side edges thereof, of couplings formed with recesses for receiving 95 each a pair of the studs, said couplings exerting an equalizing strain upon the body, and means carried by the couplings for locking the studs within the recesses.

7. A device of the character described 100 comprising an anchorage formed with spaced, aligned studs, a coupling formed with a recess for receiving the studs, an eye formed upon the coupling and disposed for normal location between the studs when the 105 coupling is engaged therewith, and a spring pressed pawl carried by the coupling for obstructing the recess to prevent accidental removal of the coupling from the studs.

In testimony whereof, I affix my signature 110 hereto.

BENJAMIN KUGLER.
